UNITED STATES PATENT OFFICE.

DAVID ROUSSEAU AND WILLIAM C. SMITH, OF NEW YORK, N. Y., ASSIGNEES
TO WILLIAM F. SMITH AND SAMUEL SAMUELS, OF SAME PLACE.

IMPROVEMENT IN SELF-LOCKING RAILROAD-SWITCHES.

Specification forming part of Letters Patent No. 176,691, dated April 25, 1876; application filed
February 29, 1876.

To all whom it may concern:

Be it known that we, DAVID ROUSSEAU and WILLIAM C. SMITH, both of New York city, in the county of New York and State of New York, have invented a new and Improved Automatic Switch-Lock for Railroads, of which the following is a specification:

Figures 1 and 2 are top views of our improved switch - lock, the switch - rail being shown in different positions. Fig. 3 is a vertical transverse section of the same, on the line *c c*, Fig. 1. Figs. 4 and 5 are side views of the same.

Similar letters of reference indicate corresponding parts in all the figures.

This invention relates to a new means of locking the switch-rails in their respective positions; and consists in the application over the rod which moves the switch of a vibrating bar or lever, which has a projecting lug for entering sockets in said rod, and a V-shaped cam, to be raised out of said sockets by the actuating lever or finger, all as hereinafter more fully described.

In the accompanying drawing, the letter A represents one of a pair of switch-rails. B is a rail of the main track, and C a rail of the side track. Fig. 1 shows the switch-rail A in line with the rail B, while in Fig. 2 it is shown in line with the rail C. D is the sliding rod, connected with the switch-rail in usual manner, and employed as part of the mechanism for moving such switch-rail. E is a vibrating finger or lever, which, when turned by the switch-tender, will strike either one of two projections, shoulders, or pins, *a b*, on the rod D, and thereby move said rod in the desired direction. Instead of pivoting the actuating-finger E, it may be caused to slide and strike the pins *a b* with equal effect. The parts hereinabove referred to are well known, and not of our invention.

F is our improved locking-lever. It is at or near one end pivoted, by a pin, *d*, to a fixed ear, *e*, which ear may be bolted or otherwise secured to one of the sleepers, or to the bed of the track. The lever F, by its own weight, will fall upon the rod D, across the end of the finger E, and has a downwardly-projecting lug, *f*, which is adapted to engage one of two sockets or mortises, *g* and *h*, that are formed in or on the rod D—that is to say,

when the rail A is in line with the rail B, the lug *f* enters the mortise *h*, as in Fig. 1; but when the switch-rail is in line with the rail C, the lug *f* enters the mortise *g*, as in Fig. 2.

By thus entering these mortises or sockets, the lever F locks the rod D, and with it the switch-rails, in the desired position, and prevents the same from being displaced otherwise than by the will of the switch - tender. The lever F is moreover made with a V-shaped projection, *i j*, at its lower side, of which, in the state of rest, the deepest middle portion will bear upon the rod D in line with that one of the pins *a b* which is next to be struck by the finger E. Thus, when the switch connects with the side track, the lower extremity of the V projection will rest on the rod D near to the pin *a*, so that when afterward the finger E is moved toward the pin *a* for moving the switch, said finger will first strike the inclined edge *j* of said V projection, and raise the lever F out of the mortise *g*, and then strike the pin *a* and move the switch; but when the switch is in line with the main track, the deeper part of the V projection will be near the pin *b*, so that the finger E, when moved toward *b*, will first strike the edge *i* of the V projection and raise the lever F out of the mortise *h*.

The lock F *f i j* operates thus quite automatically. It drops by its own weight into the mortise of the rod D as soon as the switch has reached the required position, and is nevertheless lifted out of the mortise by the finger E before said finger strikes the projection *a* or *b* to move the rod D.

We claim as our invention—

1. The switch-locking lever F, made with the projecting lug *f*, and with the two oppositely-inclined edges, *i* and *j*, to operate substantially as specified.

2. In combination with the finger E, and with the rod D, which has the projections *a* and *b*, the locking-lever F, arranged to lock the rod D and to be raised by the same finger E that actuates said rod, substantially as specified.

DAVID ROUSSEAU.
W. C. SMITH.
